UNITED STATES PATENT OFFICE

OSCAR C. SCHROEDER, OF CHICAGO, ILLINOIS

FLUID-PRESSURE-CONTROLLED CONTROLLING MECHANISM

Original application filed March 12, 1927, Serial No. 174,782, now Patent No. 1,689,803. Divided and this application filed September 29, 1928. Serial No. 309,225.

My invention relates, more particularly, to controlling mechanism for use where it is desired that a device or apparatus be operated responsive to heat conditions at a certain location, as for example in the case of oil burners where it is desired that the operation of the burner be controlled responsive to conditions at the burner.

My primary object is to provide a novel, simple and positively operating construction of controlling device of the type above referred to.

Another object is to provide a construction of such device which, while sensitive in its operation, will not easily become out of order; and other objects as will be manifest from the following description.

The present application is a division of my pending application for U. S. Letters Patent Serial No. 174,782, filed March 12, 1927, upon which Letters Patent No. 1,689,803 were granted October 30, 1928.

While my present invention may be used to advantage in many different situations and in connection with many different kinds of apparatuses, I have devised it for use more particularly as a controlling element of automatic oil burner apparatus, such as for example that disclosed in my said pending application, and have therefore chosen to illustrate it in connection with burner control apparatus and more particularly the apparatus disclosed in my said pending application.

Referring to the accompanying drawings:—

Figure 1 is a view in elevation, with certain parts sectioned of the lower portion of a furnace structure equipped with an oil burner controlled by mechanism comprising, as one of the controlling elements thereof, a controlling device embodying my invention.

Figure 2 is a view in vertical sectional elevation of my improved controlling device showing it as associated with a switch controlled thereby and forming a part of the burner control apparatus, the parts shown being in the condition assumed by them when the switch illustrated is in closed condition; and

Figure 3, a similar view of the switch mech-

anism of Fig. 2 showing it in open position.

Referring to Fig. 1, the construction therein shown comprises a furnace 4 containing a combustion chamber 5 in an opening 6 of the bottom wall 7 of which a burner 8 is located.

The burner shown, and in connection with which I have chosen to illustrate my invention, is of the type disclosed in U. S. Letters Patent No. 1,505,607 granted to me on August 19, 1924. As the form of the burner has nothing to do with my present invention, description thereof appears to be unnecessary. It may be stated, however, that the burner is so constructed that the fuel issues therefrom at 9 throughout the periphery of the upper end of the burner as represented at 10 when the motor 11 is running.

Located to one side of the burner proper 8 is a pilot tube 12 adapted to be supplied with gas through a pipe 13 leading to a source of constant supply and controlled through the medium of electrical controlling mechanism represented generally at 14, the tube 12 being so disposed that the flame produced by the igniting of the gas issuing therefrom will ignite the fuel discharged from the burner 8, there being associated with this pilot tube electrical igniter means comprising the two electrodes 15 and 16 which are spaced apart to present a spark gap intersecting the upper flow of the gas from the tube 12, these electrodes to be supplied with current to produce sparking at this gap, by electrical mechanism represented generally at 17.

At the side of the burner 8 opposite that at which the pilot tube 12 extends, is a switch device represented generally at 18 which is heat-controlled by mechanism represented generally at 19 and embodying my invention, this switch device being provided as one of the controlling elements, for the burner controlling mechanism as clearly disclosed in my said pending application Ser. No. 174,782, which issued as Patent No. 1,689,803, this switch being operative responsive to changes in temperature condition at the burner 8. The switch 18 remains in normal, circuit-closed, condition in case of failure of ignition of the fuel at the burner; is operated out of normal position following the ignition of the

fuel at the burner, and returns to normal position following extinguishment of the flame at the burner.

The mechanism 19, according to the particular construction shown, comprises a hollow body 20 shown as of tubular form and closed except for an opening in its lower end at which it communicates with a pipe 21.

The side walls and top of the hollow body 20 are preferably constructed of relatively thin metal to permit of the quick heating of the contents of the member 20 by the subjection thereof to the heat of the flame produced by the oil in burning as it issues from the burner 8, and the cooling of such contents by the action of the atmosphere, upon the extinguishment of the flame.

The pipe 21 shown as carrying the member 20, is carried by, and communicates with, a chamber 22 in a bracket-head 23 supported on a rod 24 in turn carried by an arm 25 supported, on a post 26 forming, with other posts 27 and 28, legs for supporting the burner structure.

The chamber 22 contains a hollow member 29 having a depending, restricted, open-ended, cylindrical portion 30 opening at its lower end into the chamber 22 and at its upper end into the space 31 provided by the member 29, the space 31 opening at its upper end to the atmosphere through an opening 32 in the side wall of the member 29 communicating with a passage 33 in the wall of the chamber 22.

Reciprocable in the cylinder 30 is a piston 34 containing passages 35 and 36 extending lengthwise therethrough, the lower end of the passage 35 and the upper end of the passage 36 having valve seats for downwardly and upwardly opening check valves 37 and 38, respectively, the seating-springs for which are represented at 39 and 40, respectively.

The piston 34 is pivotally connected with the lower end of a link 41, the upper end of which extends through an opening 42 in a plate 43 fitting down on the top of the member 29, and pivotally connects with a lever 44 pivoted at one end, at 45, on a stud 46 rising from the plate 43.

The other end of the lever 44 is provided with an arm 47 pivoted between its ends at 48 to the lever 44, the lower end of the arm 47 carrying a roller 49 and its upper end connected with a coil spring 50 the other end of which connects with a lug 51 on the lever 44.

The roller-equipped end of the arm 47 cooperates with the movable contact lever 52 of the switch 18, this contact lever being pivoted between its ends, as indicated at 53, to a stationary contact post 54, the contact lever 52 cooperating with a stationary contact 55 forming the other element of the switch 18.

The parts above described are so con-

structed and arranged, as shown, that when the piston 34 is in lowermost position, (Fig. 2), the switch 18 will be closed and when the piston 34 is raised to raise the lever 44 to the position shown in Fig. 3, the switch 18 will be open. 70

It may be here stated that in the relatively cold condition of the member 20, namely, when the burner is not operating, the switch device 18 assumes the position shown in Fig. 2 and the electrical circuit is closed at this point. Upon the application of heat to the member 20, as for example by the flame created by the burner 8 in operating, the air in the member 20 becomes heated, thereupon expanding and producing a pressure within the chamber 22 causing the piston 34 to rise and rock the switch arm 52 controlled thereby to a position in which the circuit is broken at this point (Fig. 3). 75 80 85

The spring 40 is so tensioned that so long as the temperature of the member 20 rises or, after rising, remains substantially constant, the piston 34 will be in raised position and the circuit through the switch device 18 broken, excess pressure generated in the member 20 escaping therefrom into chamber 22 and thence past valve 38 and through port 32 and passage 33 to the atmosphere. In other words, the construction referred to, by properly tensioning the spring 40 imprisons, against escape, air up to a certain pressure sufficient to hold the piston 34 raised and the switch device 18 in circuit open position, excess pressure generated in the receptacle 20 escaping to the atmosphere past the valve 38. 100 105 110

Upon the cooling of the receptacle 20 which results upon the extinguishment of the flame produced by the burner, this cooling effect being augmented by providing a flue 56 shown in Fig. 1 for the upward circulation of air around the member 20, the air in the member 20 contracts with the result that the piston 34 lowers returning the switch device 18, connected therewith, to the circuit closed position represented in Fig. 2, and when the pressure of the air in the member 20 becomes reduced below a predetermined degree, determined by the tension of the spring 39, air from the atmosphere will be sucked into it by passing through passage 33, port 32, piston passage 35, and past valve 37. 115

It is preferred that the chamber 22 be charged with any suitable sealing oil which, by way of example, may extend to the level represented by the line 57, to the end that the piston 34 will operate smoothly and desirable clearance between the piston and the cylinder 30 provided without leakage of air past the piston 34. 120 125

When oil is used in the device as stated the expansion of the air in member 20 produces a pressure upon the upper surface of the oil in chamber 22, the oil thus subjected to pressure, acting from below against the piston 34 130

and causing the latter to rise and rock the switch arm 52 controlled thereby to a position in which the circuit is broken (Fig. 3). Should pressure continue to be exerted in the member 20 after the piston 34 has reached the limit of its upward movement, oil beneath the piston will become forced past the check valve 38 and into the chamber 31. Should the pressure in member 20 continue to increase to an extent sufficient to force all of the oil from chamber 22 below the lower edge of cylinder 30, thus breaking the oil seal, the excess air pressure will then pass from chamber 22 around the lower edge of cylinder 30 and escape through the oil and past the valve 38 and through the oil thereabove to the atmosphere through the outlet 32. The device is so constructed as shown that the volume of oil is such that it exceeds the amount required for effecting the movement of the piston 34 from the position shown in Fig. 2 to its uppermost position.

When the member 20 cools the oil displaced from chamber 22 as stated will again flow into the chamber 22 and the continuing reduction of temperature of the air in member 20 will lower the oil in cylinder 30 below its lower edge thereby permitting air from the atmosphere to pass around the lower edge of cylinder 30 and up through the body of oil in chamber 22. Manifestly the point in the operation of the apparatus at which air will pass beneath the cylinder 30 will depend upon the amount of oil used in the apparatus, the idea of providing for the operation as stated being to render the apparatus quickly responsive to changes in the pressure of the air in member 20.

By providing the oil of relatively small volume as stated the fit of the moving parts of the piston and cylinder mechanism, including the valves 37 and 38, may be much looser than where the piston or valves are exposed directly to the operating air pressure. Furthermore, the excess air pressure generated in member 20 quickly vents past the valve 38 after the piston 34 has performed its work by movement in one direction and the oil in chamber 22 has lowered below the lower edge of the cylinder 30, and the air from the atmosphere quickly enters the device under the suction action exerted thereon by the cooling of the member 20 after the piston has performed its work by movement in the opposite direction and the oil has lowered in the cylinder 30 below the lower edge of the latter, whereby after completing its working stroke in one direction the mechanism is quickly conditioned for performing work by operation in the opposite direction, such quick conditioning action being highly desirable, as for example, when the device forms an element of an oil burner control mechanism.

By forming the chambers 22 and 31 as shown and by preference, of larger diameter

than the cylinder 30, the oil in the movement of the piston 34 in each direction is permitted to spread out and thus exertion of head pressure by the oil is greatly minimized.

It will be understood from the foregoing that a device constructed in accordance with my invention will be positive and sensitive in operation, responding quickly to changes of temperature at the burner.

The port 32 not only serves as an opening through which the air passes in the operation of the device as stated, but also serves as a vent through which excess of oil if charged into the apparatus, may escape.

While I have illustrated and described a particular construction embodying my invention, and have shown it for use in a particular connection, I do not wish to be understood as intending to limit it to the particular form shown nor to its use in apparatus of either the specific or general character stated.

What I claim as new, and desire to secure by Letters Patent, is:

1. In a device of the character described, the combination of an air chamber for subjection to heat, means operating responsive to the expansion and contraction of the air in said chamber and comprising a movable element and an oil seal subjected to the variations of air pressure in said air chamber and movable responsive thereto and in such movements controlling the position of said movable element, the structure containing inlet and outlet ports through which pressure in the continuing of expansion of the air in the chamber is relieved and suction in the continuing contraction of the air in said air chamber is relieved, respectively, and valves for said ports, said oil seal comprising such an amount of oil and the ports of the apparatus being so proportioned and arranged that following the conclusion of the movement of said element in either direction the oil seal may become broken by the air pressure against it and permit of the escape of air past said oil seal.

2. In a device of the character described, the combination of an air chamber for subjection to heat, a cylinder in communication at one end with said chamber, a piston in said cylinder containing passages in communication with said chamber and with the opposite end of said cylinder, oppositely closing check valves in said passages, means limiting the movement of said piston in opposite directions, and an oil seal for said piston subjected to the air pressure in said air chamber and operating to control the position of said piston responsive to the air pressure in said chamber, said valves being immersed in said oil seal.

3. In a device of the character described, the combination of an air chamber for subjection to heat, a cylinder in communication with said air chamber, a piston in said cylin-

der containing passages therethrough opening to the atmosphere and in communication with said chamber, oppositely closing check valves controlling said passages, means limiting the movement of said piston in opposite directions, and an oil seal for said piston subjected to the air pressure in said air chamber and operating to control the position of said piston responsive to the air pressure in said chamber, said valves being immersed in said oil seal.

4. In a device of the character described, the combination of an air chamber for subjection to heat, means operating responsive to the expansion and contraction of the air in said chamber and comprising a movable element and an oil seal subjected to the variations of air pressure in said air chamber and movable responsive thereto and in such movements controlling the position of said movable element, the structure containing inlet and outlet ports, and check valves at said ports, the pressure in the continuing of expansion of the air in the chamber being relieved and suction in the continuing contraction of the air in said air chamber being relieved through said ports, respectively, said oil seal comprising such an amount of oil and the parts of the apparatus being so proportioned and arranged that following the conclusion of the movement of said element in either direction the oil seal may become broken by the air pressure against it and permits of the escape of air past said oil seal.

5. In a device of the character described, the combination of an air chamber for subjection to heat, means operating responsive to the expansion and contraction of the air in said chamber and comprising a movable element and an oil seal subjected to the variations of air pressure in said air chamber and movable responsive thereto and in such movements controlling the position of said movable element, the structure containing inlet and outlet ports, and check valves at said ports the pressure in the continuing of expansion of the air in the chamber being relieved and suction in the continuing contraction of the air in said air chamber being relieved through said ports, respectively, said valves being immersed in said oil seal, said oil seal comprising such an amount of oil and the parts of the apparatus being so proportioned and arranged that following the conclusion of the movement of said element in either direction the oil seal may become broken by the air pressure against it and permits of the escape of air past said oil seal.

6. In a device of the character described, the combination of an air chamber for subjection to heat, means operating responsive to the expansion and contraction of the air in said chamber and comprising a movable element and an oil seal subjected to the vari-

ations of air pressure in said air chamber and movable responsive thereto and in such movements controlling the position of said movable element, said movable element containing inlet and outlet ports, and valves at said ports, the pressure in the continuing of expansion of the air in the chamber being relieved and suction in the continuing contraction of the air in said air chamber being relieved through said ports, respectively, said oil seal comprising such an amount of oil and the parts of the apparatus being so proportioned and arranged that following the conclusion of the movement of said element in either direction the oil seal may become broken by the air pressure against it and permits of the escape of air past said oil seal.

7. In a device of the character described, the combination of an air chamber for subjection to heat, means operating responsive to the expansion and contraction of the air in said chamber and comprising a movable element and an oil seal subjected to the variations of air pressure in said air chamber and movable responsive thereto and in such movements controlling the position of said movable element, said movable element containing inlet and outlet ports, and check valves for said ports, the pressure in the continuing of expansion of the air in the chamber being relieved and suction in the continuing contraction of the air in said air chamber being relieved through said ports, respectively, said oil seal comprising such an amount of oil and the parts of the apparatus being so proportioned and arranged that following the conclusion of the movement of said element in either direction the oil seal may become broken by the air pressure against it and permits of the escape of air past said oil seal.

8. In a device of the character set forth, the combination of an air chamber for subjection to heat, an oil well in communication with said chamber, a cylinder extending into said well and opening into the latter below the level of the oil in said well, a piston in said cylinder, the structure containing inlet and outlet ports, and valves at said ports, the pressure in the continuing of expansion of the air in said chamber being relieved and suction in the continuing contraction of the air in said chamber being relieved through said ports, respectively.

9. In a device of the character set forth, the combination of an air chamber for subjection to heat, an oil well in communication with said chamber, a cylinder extending into said well and opening into the latter below the level of the oil in said well, a piston in said cylinder, the structure containing inlet and outlet ports, and check valves at said portions, the pressure in the continuing of expansion of the air in said chamber being relieved and suction in the continuing con-

traction of the air in said chamber being relieved through said ports, respectively.

10. In a device of the character set forth, the combination of an air chamber for subjection to heat, an oil well in communication with said chamber above the oil level in said well, a cylinder extending into said well and opening into the latter, a piston in said cylinder, the structure containing inlet and outlet ports, and valves at said ports, the pressure in the continuing of expansion of the air in said chamber being relieved and suction in the continuing contraction of the air in said chamber being relieved through said ports, respectively.

11. In a device of the character set forth, the combination of an air chamber for subjection to heat, a cylinder in communication at one end with said chamber and having an expanded upper portion, a piston in said cylinder, an oil seal for said piston subjected to the air pressure in said air chamber and operating to control the position of said piston responsive to the air pressure in said chamber, the structure containing inlet and outlet ports and valves at said ports, the pressure in the continuing of expansion of the air in the chamber being relieved and suction in the continuing contraction of the air in said chamber being relieved through said ports, respectively.

12. In a device of the character set forth, the combination of a chamber for subjection to heat, an oil well in communication with said chamber, a cylinder extending into said well and opening into the latter below the level of the oil therein, said cylinder having an expanded upper portion, a piston in said cylinder, said oil well providing an oil seal for said piston subjected to the air pressure in said air chamber and operating to control the position of said piston responsive to the air pressure in said chamber, the structure containing inlet and outlet ports, and valves at said ports, the pressure in the continuing expansion of the air in said chamber being relieved and suction in the continuing contraction of the air in said chamber being relieved through said ports, respectively.

13. In a device of the character described, the combination of an air chamber for subjection to heat, means operating responsive to the expansion and contraction of the air in said chamber and comprising a movable element and an oil seal subjected to the variations of air pressure in said air chamber and movable responsive thereto and in such movements controlling the position of said movable element, the structure containing inlet and outlet ports, and check valves for said ports, the pressure in the continuing of expansion of the air in the chamber being relieved and suction in the continuing contraction of the air in said chamber being relieved, respectively, through said ports,

and means limiting the movement of said element in opposite directions, said oil seal comprising such an amount of oil and the parts of the apparatus being so proportioned and arranged that following the conclusion of the movement of said element in either direction the oil seal may become broken by the air pressure against it and permits the escape of air past said oil seal.

14. In a device of the character described, the combination of an air chamber for subjection to heat, means operating responsive to the expansion and contraction of the air in said chamber and comprising a movable element and an oil seal subjected to the variations of air pressure in said air chamber and movable responsive thereto and in such movements controlling the position of said movable element, the structure containing inlet and outlet ports through which pressure in the continuing of expansion of the air in the chamber is relieved and suction in the continuing contraction of the air in said air chamber is relieved, respectively, and valves for said ports, said valves being immersed in said oil seal, said oil seal comprising such an amount of oil and the parts of the apparatus being so proportioned and arranged that following the conclusion of the movement of said element in either direction the oil seal may become broken by the air pressure against it and permit of the escape of air past said oil seal.
